US00D983744S

(12) **United States Design Patent** (10) **Patent No.:** **US D983,744 S**
(45) **Date of Patent:** **** Apr. 18, 2023**

(54) **COMBINED CRADLE WITH CHARGING PAD FOR WIRELESS EARPHONES**

(71) Applicant: **LG ELECTRONICS INC.**, Seoul (KR)

(72) Inventors: **Byunghyun Yi**, Seoul (KR); **Soonhyun Park**, Seoul (KR); **Gangho Woo**, Seoul (KR)

(73) Assignee: **LG ELECTRONICS INC.**, Seoul (KR)

(**) Term: **15 Years**

(21) Appl. No.: **35/512,885**

(22) Filed: **May 12, 2021**

(80) **Hague Agreement Data**

Int. Filing Date: **May 12, 2021**
Int. Reg. No.: **DM/214310**
Int. Reg. Date: **May 12, 2021**
Int. Reg. Pub. Date: **Nov. 12, 2021**

(30) **Foreign Application Priority Data**

Dec. 8, 2020 (KR) 30-2020-0060364

(51) **LOC (14) Cl.** **13-02**

(52) **U.S. Cl.**

USPC **D13/108; D3/294**

(57) **CLAIM**

The ornamental design for a combined cradle with charging pad for wireless earphones, as shown and described.

DESCRIPTION

1. Combined cradle with charging pad for wireless earphones

1.1 : Perspective

1.2 : Front

1.3 : Back

1.4 : Left

1.5 : Right

1.6 : Top

1.7 : Bottom

1.8 : Perspective view in condition of use

1.9 : Perspective view in a closed state

The broken lines indicate portions of the article that form no part of the claimed design; the broken line showing of the wireless earphones is provided for the purpose of illustrating environmental structure and form no part of the claimed design.

1 Claim, 9 Drawing Sheets
